LADY'S STOCKING

David H. Setzer, Valdese, N. C., assignor to Waldensian Hosiery Mills, Incorporated, Valdese, N. C., a corporation of North Carolina

Application June 23, 1952, Serial No. 20,309

Term of patent 14 years

(Cl. D47—7)

To all whom it may concern:

Be it known that I, David H. Setzer, a citizen of the United States of America, residing at Valdese, in the county of Burke, State of North Carolina, have invented a new, original, and ornamental Design for a Lady's Stocking, of which the following is a specification, reference being had to the accompanying drawings, forming a part thereof.

I claim:

The ornamental design for a lady's stocking, substantially as shown.

DAVID H. SETZER.
